R. C. CHARLTON

LEVEL

Filed Nov. 17, 1926

UNITED STATES PATENT OFFICE.

RICHARD C. CHARLTON, OF PHILADELPHIA, PENNSYLVANIA, ASSIGNOR TO HENRY DISSTON & SONS, INCORPORATED, OF PHILADELPHIA, PENNSYLVANIA, A CORPORATION OF PENNSYLVANIA.

LEVEL.

Application filed November 17, 1926. Serial No. 148,928.

My invention relates to certain improvements in spirit levels and plumbs of the type having either a single view-opening for a level or plumb-tube, or having a series of openings for the said tubes.

The object of my invention is to make a comparatively light level of metal, preferably aluminum alloy, and to so design the parts that they can be readily assembled, and when assembled the same will be rigid and the edges will be true.

In the accompanying drawings:

Fig. 1 is a side view of my improved level and plumb;

Fig. 2 is a longitudinal sectional view on the line 2—2, of Fig. 1;

Fig. 3 is a transverse sectional view on the line 3—3, Fig. 1;

Fig. 4 is a transverse sectional view on the line 4—4, Fig. 1;

Fig. 5 is a detached perspective view of parts of the level;

Fig. 6 is a detached sectional view of the level-tube holder; and

Fig. 7 is a plan view of the same.

The frame 10 of the level is made of bars of extruded metal, preferably aluminum alloy. The bars are T-shaped in cross-section as shown in Fig. 5. The end bars 11 are secured to the side bars 12 by screws or other fastenings.

At each side of the level are metal plates 13, preferably of aluminum alloy. These plates are thin and wide. The plates are secured to the T-flanges of the bars 11 and 12 that make up the frame. In the present instance, bolts 14 are used as shown in Fig. 3, but other fastening means may be used if desired.

In order to provide room for the level-glass holders, washers 15, preferably of metal, are located between the plates and the ribs of the bars through which the bolts extend.

The plates 13 are perforated at 16 to provide sight openings through which the level-tubes are exposed.

The spirit tubes 17 are made as shown in Figs. 4 and 6. Their ends are closed and are embedded in plaster of Paris 18 located in cavities 19 in the holders 20. These holders are of a thickness to fit between the two

plates 13—13 and have narrow extensions 21 which rest against the bars 12—12 and are secured to said bars by screws 24. Circular frames 22 are located on each side of the level, and through-bolts 23 extend through the frames and plates and through the tube-holders, firmly securing the several parts together.

This construction makes a very light and substantial metallic level and plumb, and when made of aluminum the frame can be the natural color, while the side plates can be treated to imitate walnut, mahogany, or any woods, making a very attractive article of manufacture.

The level can be made with a single opening for either a level-tube or a plumb-tube, or it can be made with two or more openings. In the present instance there are three openings. In the central opening there are two level-tubes, while in each end opening is a plumb-tube. The openings may be glazed if desired.

In the claims, the term "level" is used to include either a level or a plumb, or a combined level and plumb.

I claim:

1. The combination in a level, of a frame made of T-shaped bars; a body portion consisting of two plates spaced apart; means for securing the plates to the T-web of the bars, the heads of the T-shaped bars extending laterally beyond the plates, each of said plates having an opening; and a spirit tube located in the space between the plates opposite the openings.

2. The combination in a level, of a frame made of T-shaped bars secured together; two thin plates set in back of the flanges of the frame; means for securing said plates to the T-web of the frame; a holder located between the plates and between the T-webs of the frame, said holder having extensions at each end; means for securing the extensions to the T-web of the frame; and a spirit tube in said holder, the plates having openings opposite the spirit tube.

3. The combination in a level, of a frame consisting of side bars and end bars, the bars being T-shaped in cross-section; means for securing the end bars to the side bars; two thin plates located on each side of the

T-web of the bars and fitting in the space between the flanges of said bars; transverse bolts securing the plates to the T-web of the bars; spirit tube holders located in the space between the plates, said holders having extensions resting against the T-web of the frame and having an open centre;

spirit tubes extending across the openings, the plates having openings in alignment with the openings in the holders; frames surrounding the openings; and bolts securing the several parts together. ¹⁰

RICHARD C. CHARLTON.
